UNITED STATES PATENT OFFICE.

FREDERICK A. SCHIERBERG, OF ST. LOUIS, MISSOURI.

CAR-REGISTER.

SPECIFICATION forming part of Letters Patent No. 784,595, dated March 14, 1905.

Application filed October 25, 1904. Serial No. 229,987.

To all whom it may concern:

Be it known that I, FREDERICK A. SCHIERBERG, a citizen of the United States, and a resident of St. Louis, Missouri, have invented 5 certain new and useful Improvements in Car-Registers, of which the following is a specification containing a full, clear, and exact description, reference being had to the accompanying drawings, forming a part hereof.

10 My invention relates to improvements in car-recorders; and it consists in the novel features herein shown, described, and claimed.

Figure 1 is a side elevation of a railway-track, showing my car-recorder in position 15 for use, the car-truck being shown in dotted lines. Fig. 2 is a top plan view of the railway-track, showing the recorders in position for use as in Fig. 1, the car-truck and recorder-operating mechanism carried by the 20 car-truck being omitted. Fig. 3 is a top plan view, upon an enlarged scale, of the recorder-operating mechanism carried by the car-truck, the car-truck being omitted. Fig. 4 is an enlarged sectional detail through the 25 recorder-operating mechanism and through the recorder, the view being taken on the line 4 4 of Fig. 3 with reference to the recorder-operating mechanism and on the line 4 4 of Fig. 2 with reference to the recording 30 mechanism. Fig. 5 is an enlarged sectional detail through the center of the recording mechanism on a line crosswise of Fig. 4, said view being taken on the line 5 5 of Fig. 2 with regard to the recording mechanism and upon 35 the line 5 5 of Fig. 4 with the regard to the combination. Fig. 6 is an enlarged side elevation showing the connection between the recorder-operating mechanism and the recorder, the other parts being omitted. Fig. 40 7 is an enlarged sectional detail of the step-by-step mechanism for advancing the recording-ribbons.

Referring to the drawings in detail, the recording mechanism is mounted upon the ties 45 just inside of the rails, there being one recorder or series of recorders just inside of one of the rails and another recorder or series of recorders just inside of the other rail, so that the first series of recorders will be operated 50 by a train going in one direction and the

other series of recorders will be operated by a train going in the opposite direction. Each recording mechanism comprises a base-plate 10 and a casing mounted upon the base-plate, said casing having guide-grooves 11 and 12, said grooves being open at both ends and flaring, there being gear-teeth 13 between said grooves, the upper paper-roller 14, mounted in the casing, a carbon-roller 15, mounted in the casing, the lower paper-roller 16, mounted in the casing, the guide-bar printing-plate 17, mounted transversely at the center of the casing in position to gather the two strips of paper and the strip of carbon for simultaneous printing, feed-rollers 18 and 19, mounted on the opposite side of the guide-bar from the paper-rollers, and mechanism for operating the feed-rollers from the passing train. A transverse slot 21 is formed between the last two of the gear-teeth 13 immediately 70 above the guide-bar 17. The feed-rollers 18 and 19 are mounted in posts 22. The spindle 23 of the roller 18 extends some distance through one of the posts, as shown in Fig. 7. A sprocket-wheel 24 is loosely mounted upon 75 the outer end of the spindle 23 outside of the post. A ratchet-wheel 25 is fixed upon the spindle outside of the sprocket-wheel, and a pawl 26, carried by the sprocket-wheel, engages the teeth of the ratchet-wheel 25, so that 80 when the sprocket-wheel moves forwardly the feed-roller is moved forwardly and when the sprocket-wheel moves backwardly the feed-roller stands still. A spring 27 connects the sprocket-wheel 24 to one of the posts 22. 85 An idler sprocket-wheel 28 is mounted upon a stub-shaft 29, and a sprocket-chain 30 is mounted upon the sprockets 24 and 28. An operating-arm 31 extends from the sprocket-chain horizontally through a slot 32 into the 90 groove 11.

The mechanism for operating the recorder is carried by the car-truck. An attaching-plate 33 is secured to the car-truck and has gears 34 at its forward ends. Segmental 95 arms 35 and 36 extend inwardly from the forward ends of the attaching-plate 33 just back of the ears 34, said arms being concentric to the perforations in the ears. The hinged arm 37 is connected to the ears 34 by a bolt 100

38, said arms swinging between the arms 35 and 36. A cross-piece 39 is formed integral with the arm 37 immediately outside of the arms 35 and 36 and the grooved side piece 39, 5 the inner face of said arms having channels 42. A plate 43 is slidingly mounted with its edges in the channels 42, said plate being shorter than the side pieces 40 and 41, so as to allow it to slide back and forth endwise. 10 A cross-piece 44 is bolted to the inner ends of the sides 40 and 41, and springs 45 and 46 connect the plate 43 to the cross-pieces 39 and 44, respectively, the tension of said springs being exerted to hold the plate 43 in position 15 relative to the end pieces. Bearing-blocks 47, 48, and 49 extend upwardly from the plate 43, said bearing-blocks being bored from the lower side of the plate to form the stop-housings 50, the sliding-bolt bearing 51, 20 the spring-casing 52, and the spring stem-bearing 53. The stops 54 are slidingly mounted in the housing 50. The sliding bolt 55 is slidingly mounted in the bearing 51. The spring 56 is mounted in the casing 52 against 25 the upper end of the bolt 55, and the stem 57 extends upwardly from the upper end of the bolt through the spring into the bearing 53. The shanks 58 extend downwardly from the stops 54. A retaining-plate 59 has openings 30 through which the shanks 58 extend, and said plate is bolted to the plate 43 to engage the stops 54 and hold the sliding bolts in position. A roller-frame 60 is hinged to the lower end of the shanks in the bearing-blocks 47 and 49. 35 Rollers 61 are mounted in these frames to engage in the grooves 11 and 12. The roller-frames 60 are hinged to the shanks, so that the roller may swing forwardly and not backwardly, as shown in Fig. 6. Springs 62 40 are secured to the shanks and extend downwardly to engage the roller-frames and hold the roller-frames yieldingly in their vertical positions. A spring-dog 63 extends downwardly from the lower end of one of the 45 springs 62 in position to engage the operating-arm 31. A printing-roller frame 64 is hinged to the lower end of the central one of the shanks 58, there being a spring 65 secured to the shanks to engage the roller-frame and 50 hold it in its normal vertical position, so that the roller may swing forwardly and not backwardly. The printing-roller is in the form of a cross, the arms 66 carrying the printing characters, said arms being adapted to engage between the gear-teeth 13 as the car approaches the recording device, said gear-teeth serving to straighten the roller and get it lined up so that it will print upon the paper through the slot 21 as the car passes the recording device. 55 A star 67 is secured to the end of the spindle of the printing-roller to be engaged by a spring, so that the roller will snap from one arm to the other of the star 60

and be held in position to engage the teeth 13 properly.

When the train passes the recording device, the dog 63 engages the operating-arm 31 and moves the chain 30 forwardly a step, thereby moving the feed-roller 18 and drawing the ribbons a step, so as to furnish a clean surface for the printing of the car name and number. Then as the dog 63 passes out of engagement with the operating-arm the chain moves backwardly under the tension of the spring 27, so as to bring the operating-arm back to its normal position and ready for another movement forwardly.

The car names or numbers are impressed or engraved upon the edges of the arms 66, and each car carries the recorder-operating device, so that when a train of cars passes a certain recorder the names and numbers of the car will be printed upon the ribbons in the recording device.

The printing-roller normally occupies the 85 position shown in full lines in Fig. 3 and is in position to engage the recording mechanism. When it is desired to swing the printing-roller out of line with the recording mechanism, the frame is turned to the position shown 90 in dotted lines in Fig. 3. The frame is held in its operative position by the step-screw 68, mounted in the arm 35.

I claim—

1. In a car-recorder: a series of recording 95 mechanisms adapted to be mounted inside of one of the rails; a second series adapted to be mounted inside of the other rail; and operating mechanism adapted to be carried by the cars so that when the car runs one way it 100 will operate one series of recorders, and so that when the car runs the other way it will operate the other series of recorders.

2. In a car-recorder: a recording mechanism adapted to be mounted upon the track 105 and having paper to receive the record and recorder-operating mechanism adapted to be carried by the car, and having means to make a record upon the paper as the car passes along the track.

3. In a car-recorder: recording mechanisms adapted to be mounted upon the track; a recorder-operating mechanism adapted to be carried by the car; and having means of identifying the car upon the recording mechanism; said recording mechanisms and said recorder-operating mechanisms being arranged so that the record will be made by the car going in either direction.

In testimony whereof I have signed my 120 name to this specification in presence of two subscribing witnesses.

FREDERICK A. SCHIERBERG.
